CLAIM

We claim the ornamental design for a display screen or portion thereof with graphical user interface, as shown and described.

DESCRIPTION

The file of this patent application contains at least one drawing executed in color. Copies of this patent application with color drawings will be provided by the Office upon request and payment of the necessary fee.

FIG. 1 is a front view of an embodiment of the claimed design of a display screen or portion thereof with a graphical user interface;

FIG. 2 is a front view of another embodiment of the claimed design of a display screen or portion thereof with a graphical user interface;

FIG. 3 is a front view of another embodiment of the claimed design of a display screen or portion thereof with a graphical user interface;

FIG. 4 is a front view of another embodiment of the claimed design of a display screen or portion thereof with a graphical user interface;

FIG. 5 is a front view of another embodiment of the claimed design of a display screen or portion thereof with a graphical user interface; and,

FIG. 6 is a front view of another embodiment of the claimed design of a display screen or portion thereof with a graphical user interface.

The outermost broken lines in the Figures illustrate a display screen or portion thereof and form no part of the claimed design. The other broken lines in the Figures illustrate portions of the graphical user interface that form no part of the claimed design.
